UNITED STATES PATENT OFFICE.

WILLIAM REESE, OF CHESTER, WEST VIRGINIA, AND HARRY S. REESE, OF DAYTON, OHIO.

DESIGN FOR A CONE-SERVING DEVICE.

41,726.

Specification for Design.

Patented Aug. 29, 1911.

Application filed June 3, 1911. Serial No. 631,140. Term of patent 7 years.

To all whom it may concern:

Be it known that we, WILLIAM REESE, a citizen of the United States of America, residing at Chester, in the county of Hancock and State of West Virginia, and HARRY S. REESE, a citizen of the United States of America, residing at Dayton, county of Montgomery, and State of Ohio, have invented a certain new, original, and ornamental Design for a Cone-Serving Device, of which the following is a specification, reference being had to the accompanying drawing, forming a part thereof.

The figure is a perspective view of the

cone serving device, illustrating our new design.

We claim:—

The ornamental design for a cone serving device, as shown.

WILLIAM REESE.
HARRY S. REESE.
